(57) **CLAIM**

The ornamental design for a fragrance dispenser, as shown and described.

DESCRIPTION

FIG. 1 is a perspective view of a fragrance dispenser showing our new design.

FIG. 2 is a front view of the fragrance dispenser shown in FIG. 1 showing our new design.

FIG. 3 is a left side view of the fragrance dispenser shown in FIG. 1 showing our new design.

FIG. 4 is a right side view of the fragrance dispenser shown in FIG. 1 showing our new design.

FIG. 5 is a back view of a fragrance dispenser shown in FIG. 1 showing our new design.

FIG. 6 is a top view of the fragrance dispenser shown in FIG. 1 showing our new design; and,

FIG. 7 is a bottom view of the fragrance dispenser shown in FIG. 1 showing our new design.

The broken lines shown in the drawings are for illustrative purposes only and form no part of the claimed design.
